TYPE-WRITING-MACHINE KEY AND TYPE-BAR OPERATING MECHANISM.

1,105,543.

Specification of Letters Patent. Patented July 28, 1914.

Continuation of application serial No. 684,759, filed December 9, 1911. This application filed April 14, 1913, Serial No. 780,979. Renewed March 20, 1914. Serial No. 825,891.

To all whom it may concern:

Be it known that I, JESSE ALEXANDER, a citizen of the United States of America, and residing at New York, in the county of 5 Kings and State of New York, have invented new and useful Improvements in Type-Writing-Machine Key and Type-Bar Operating Mechanism, of which the following is a specification.

10 My invention relates particularly to front stroke visible writing machines.

The object of the invention is to provide a durable and easily operated mechanism with a light starting touch and yet capable 15 of heavy manifolding or other heavy work.

The invention consists in a construction the principles of which are illustrated in the accompanying two sheets of drawings. The key lever is so mounted and connected 20 with the universal bar and intermediate lever that the key lever may be readily removed and withdrawn from the front of the machine. The type bars are arranged in the arc of a circle being carried by a vertical 25 type bar plate. The key levers may be arranged in banks as is common in this art. Each key lever is connected to its corresponding type bar so that a light starting touch is provided and a more powerful 30 printing or completing stroke is effected when the stroke of the key lever is followed through. Each type bar has a number of teeth arranged around its pivot in the form of a gear segment and a toothed disk or gear 35 segment is pivotally mounted adjacent the type bar teeth to engage the same. A two-armed intermediate lever has its horizontal forwardly extending arm connected with a key lever and its vertical arm connected to 40 a link. This link has sliding engagement with a downwardly projecting lug on the type bar and has a pin and slot connection with the toothed disk which engages the type bar teeth.

45 Figure 1, is a vertical longitudinal section of a machine showing a single unit of a key and type bar action in the normal position of rest. Fig. 2, is a detail perspective view of one of the intermediate levers. Fig. 3, 50 is a detail perspective view of one of the connecting links. Fig. 4, is a detail perspective view of one of the toothed disks. Fig. 5, is a detail perspective view of one

of the type bars. Fig. 6, is a vertical cross-sectional view similar to Fig. 1 but showing 55 the action in the printing position.

The key levers such as 1 are all pivotally mounted on a rod 2 at the rear of the machine. The rear end of the key lever is forked at 3 so as to have a yielding attach- 60 able connection with the pivot rod 2. The type bar 4 is pivoted at 5 in the type bar plate 6 so as to strike against the front of the platen 7 in printing. This platen is mounted in a suitable carriage adapted to 65 traverse the machine from side to side. The intermediate lever 8 is connected to the link 9 at its upper end and the link 9 is connected to the toothed disk 10. The parts are held in the position shown by means of 70 a tension spring 11, the type bar resting in a bracket 12. The forward arm of the intermediate lever is forked as at 13 to have a sliding engagement with the pin 14 carried by the key lever 1. The adjusting 75 screw 15 operating in a stationary bar 16 is adapted to adjust the tension of the spring 11. The upward arm of the intermediate lever has a pin 17 affording a pivot in the hole 18 of the link 9. The rear end of the 80 link 9 has a slot 19 for the pin 20 on the toothed disk 10. The type bar 4 has a downwardly projecting lug or shoulder 21 engaged by the front end or tip 22 of the link 9. The intermediate levers are all mounted 85 on a pivot rod 23. The toothed disks such as 10 are pivoted as at 24 and each has a series of teeth such as 25 engaging the teeth 26 of the corresponding type bar.

When the front end of a key lever is depressed it rocks the intermediate lever about its pivot and carries the upper end of its vertical arm forward. The link 9 having a sliding connection at its rear with the pin 20 of the disk 10 is thus guided in a sub- 95 stantially straight line forward movement and the tip 22 engaging the shoulder 21 impels the type bar upward. As the type bar starts to move upward by the momentum given it by the link 9, the teeth 26 meshing 100 with the teeth 25 cause the disk 10 to rotate in a left-handed direction that is, anti-clockwise. If the stroke of the key lever is sufficiently quick and powerful the type bar will be driven to the printing position 105 by the first action of the front end 22 of

the link 9 against the lug 21. If the stroke of the key lever however, is followed through more slowly, the link 9 will take up the lost motion connection with the pin 20 so that a power connection will exist from the key lever to the type bar through the teeth 25 and 26 for exerting extra heavy pressure on the platen (see Fig. 6). When the key lever 1 is released, the spring 11 pulls back the vertical arm of the intermediate lever 8 and thus lifts the key lever. At the same time link 9 is moved rearwardly and the toothed disk 10 and type bar are swung accordingly. The rebound of the type bar from the platen also tends to throw the type bar back into the normal position of rest and also to return the intermediate lever and the key lever by reason of the connection between the teeth 26 and 25.

For the purpose of ink writing the ribbon 30 is provided and one of the spools 31 for carrying the ribbon as shown. Adjacent the printing point the ribbon is guided by a slide 32, the lower end of which is connected to the lever 33 which is pivoted at 34. The rear end of the lever 33 is pivoted to an arm 35 which carries the universal bar 36 at the lower end. This universal bar 36 extends across the machine beneath the finger 37 of each key lever so that when any key lever is depressed the universal bar 36 is depressed and the ribbon guide 32 moved to the position shown in Fig. 6, so as to interpose the ribbon in front of the type.

It will be obvious that the invention is not limited to the exact proportions, form and arrangement herein illustrated and that the claims are not intended to be limited by the particular terms employed except so far as required by the prior art.

This application is a continuation of 664,759, filed December 9, 1911.

What I claim is:—

1. In a key and type bar mechanism, a pivoted key lever, a pivoted type bar having a projecting shoulder and a series of teeth, a disk having teeth meshing with the teeth of said type bar, a link connected to said disk and having one end adapted to coöperate with said shoulder on said type bar and an intermediate lever connecting said link and said key lever.

2. In a key and type bar mechanism, a pivoted key lever, a pivoted intermediate lever connected thereto, a pivoted type bar having gear teeth and a projecting shoulder, a toothed disk meshing with the gear teeth on said type bar and a link connected to said intermediate lever, adapted to engage the shoulder of said type bar and having a lost motion connection with said toothed disk.

3. In a key and type bar mechanism, a key lever, an intermediate lever connected thereto, a pivoted type bar having gear teeth, a toothed disk meshing therewith and a link pivoted to said intermediate lever and having a lost motion connection with said toothed disk.

4. In a key and type bar mechanism, a pivoted type bar having a downwardly projecting shoulder and a series of gear teeth, a toothed disk meshing with said gear teeth, a member connected to said toothed disk and adapted to engage said shoulder and a key lever connected to operate said member.

5. In a key and type bar mechanism, a pivoted type bar having a downwardly projecting shoulder and a series of gear teeth, a toothed disk meshing with said gear teeth, a member having a lost motion connection with said toothed disk and adapted to engage said shoulder and means for operating said member.

6. In a key and type bar mechanism, a pivoted type bar having a shoulder, a disk connected to said type bar, a link connected to said disk and having one end adapted to coöperate with said shoulder, an intermediate lever connected to said link, a spring holding said lever under tension and a key lever connected to said intermediate lever.

7. In a key and type bar mechanism, a pivoted type bar having gear teeth, a toothed disk meshing therewith an intermediate lever having a vertical arm, a link pivoted to said arm and connected to said disk by a pin and slot and having one end adapted to move said type bar at the beginning of the stroke and a key lever connected to said intermediate lever.

8. In a key and type bar mechanism, a pivoted type bar having gear teeth and a shoulder, a disk having teeth meshing with the type bar teeth throughout the entire stroke of the type bar, a link connected to said disk and engaging the shoulder of said type bar at the beginning of the stroke and a key lever for operating said link.

9. In a key and type bar mechanism, a pivoted type bar having gear teeth and a shoulder, a disk having teeth meshing with the type bar teeth throughout the entire stroke of the type bar, a link connected to said disk and engaging the shoulder of said type bar at the beginning of the stroke, an intermediate lever connected to said link and a key lever for operating said intermediate lever.

JESSE ALEXANDER.
